US0D1071204S

(12) **United States Design Patent** (10) **Patent No.:** **US D1,071,204 S**
(45) **Date of Patent:** **** Apr. 15, 2025**

(54) **IN-LINE OCCLUDER**

- (71) Applicant: **ZEVEX, INC.**, Salt Lake City, UT (US)
- (72) Inventors: **David Carballo**, Alajuela (CR); **Olman Madrigal**, San Jose (CR); **J. Ryan Stanfield**, Sandy, UT (US)
- (73) Assignee: **Zevex, Inc.**, Salt Lake City, UT (US)
- (**) Term: **15 Years**
- (21) Appl. No.: **29/899,739**
- (22) Filed: **Aug. 11, 2023**

Related U.S. Application Data

(57) **CLAIM**

The ornamental design for an in-line occluder as shown and described.

DESCRIPTION

FIG. 1 is a perspective view of an in-line occluder, wherein the in-line occluder is formed of an opaque material; FIG. 2 is a front elevation view thereof; FIG. 3 is a rear elevation view thereof; FIG. 4 is a right side elevation view thereof; FIG. 5 is a left side elevation view thereof; FIG. 6 is a top plan view thereof; FIG. 7 is a bottom plan view thereof; FIG. 8 is a perspective view of the in-line occluder of FIGS. 1-7, wherein the in-line occluder is shown in an enteral feeding pump cassette environment; FIG. 9 is a front elevation view thereof; FIG. 10 is a rear elevation view thereof; FIG. 11 is a right side elevation view thereof; FIG. 12 is a left side elevation view thereof; FIG. 13 is a top plan view thereof; and, FIG. 14 is a bottom plan view thereof.

The broken line showing of the enteral feeding pump cassette in FIGS. 8-14 depicts environmental structure and forms no part of the claimed design.

1 Claim, 9 Drawing Sheets
